UNITED STATES PATENT OFFICE.

DANA H. MAYO, OF DETROIT, MICHIGAN.

BAFFLE FOR WATER-TUBE BOILERS.

Application filed July 3, 1925. Serial No. 41,373.

This invention is an improvement in baffle construction for use in water tube boiler installation. Its object is to provide means for varying the circulation area or space in the course of the gases of combustion, in proportion to the draft or pressure, by means of an adjustable baffle wall, as shown in the drawings and hereinafter described.

In the drawings showing certain preferred 10 embodiments of the invention:

Figure 1 is a view in sectional elevation showing one form of the baffle in operative position with relation to a bank of tubes.

Figure 2 is a partial sectional view in 15 front elevation.

Figure 3 is an enlarged sectional detail view showing the link connection between adjacent plate sections of a flexible baffle wall, both straight and deflected.

Figures 4 and 5 are additional detail views 20 in face and edge views respectively, showing a modified construction.

Figure 6 is a partial view similar to Fig. 1, showing a further modified arrangement, 25 utilizing a baffle member of the valve or damper type.

In the construction and operation of a typical installation of a water tube boiler of the inclined type, the banks of tubes 2 30 connecting the usual mud drum 3 with a steam or other upper drum 4, are usually provided with baffles laid across the tubes at varying positions and heights with alternating circulation spaces at top and bottom, 35 to effect tortuous travel of the gases towards the stack.

Ordinarily such baffle walls, of refractory or other suitable material, are fixed and inflexible, and not subject to change under 40 varying conditions of operation of the boiler as to draft, pressure, etc.

In my present invention I have shown one side of the bank of tubes 2 provided for a considerable distance above the mud drum 3 with a layer of plate metal or other baffle 45 5, over the top of which is a space for gas circulation downwardly. Spaced beyond baffle 5 sufficiently to provide intervening area for downgoing gases, is a similar baffle 6, closing off circulation below upper drum 50 4 towards the bottom.

The feature of improvement involved in the present invention is a flexible apron or adjustable damper valve extending below the 55 lower edge of fixed baffle 6, capable of being lengthened and shortened or otherwise ad-

justed to vary the lower circulation space or gas circulation area above the lower drum 3.

Said apron, as in Figs. 1 to 5 inclusive, is composed of a series of steel plate slat sections 7 connected together and to each other by loosely arranged links 8, as shown.

The lowermost slat is provided with any suitable terminal connection, as an angle bracket 9, to which raising and lowering 60 wires or cables 10 are connected, so that the baffle may be lengthened or shortened by winding the cables upon sheave wheels 11, to which they are connected at their upper 65 ends.

The apron is preferably composed of a series of such connected sections arranged end to end across the face of the bank of tubes, as in Fig. 2 with a corresponding sheave wheel 11 for each sectional series. 70 75 Wheels 11 are mounted on a rotatable shaft 12, carried in bearings 13 at intervals, and spaced conveniently as determined by the tubes or other conditions. Shaft 12 may be made of pipe sections with a central square or other bar 14, having at its outer end a worm wheel or other suitable gear 15 in driving engagement with a worm 16 or the like.

Bearings 13 are supported across the space 80 provided for the looped apron by fixed connection with opposite tubes, as at 17. Additional bracing supports 18 are connected with the several cross bearing supports as 85 at 19, and at the top with holding brackets 20 secured to the upper end portions of the 90 tubes, as in Fig. 1. By this means the sheaves and shaft are rotatably mounted in their bearings, and are capable of being turned for winding or unwinding to any desired extent.

When it is desired to interpose additional baffling resistance to the flow of the gases, the aprons are lowered, and when less resistance and a freer flow is wanted, they are 95 raised, as will be readily understood.

In place of the sheet or plate metal sections 7 and links 8, the aprons may be composed of cast plate sections 21 having hinge lugs 22 and 24 with connecting pins or bolts 23, as in Figs. 4 and 5. In either case the baffle walls are sufficiently flexible to allow of their assuming a looped or return bend form, as in Fig. 1, somewhat in the manner of a drop curtain.

In Figure 6 I show a further modified 110 construction in which a hinged butterfly valve or damper 26 is pivotally connected to

the lower edge of the stationary baffle section 6, as at 27. It is raised or lowered to the desired extent by cables 10 in the same manner as above described, as indicated in 5 dotted lines.

It will be obvious also that other forms of adjustable baffle sections may be substituted, as in the form of a sliding damper, and that the construction may be otherwise changed 10 or varied by the skilled mechanic within the scope of the following claims.

I claim:

1. A water tube boiler provided with an adjustable baffle composed of an upper immovable portion and a lower movable portion forming a positively connected extension thereof, said movable portion being adapted to be raised and lowered towards and from the immovable portion to vary the 20 gas circulation area.

2. A baffle wall for water tube boilers consisting of a flexible apron continuously connected with and depending below an upper fixed portion, and means for raising and lowering the lower portion of the apron.

3. A baffle wall for water tube boilers consisting of a flexible apron composed of loosely connected sections, and means for raising and lowering its lower portion only.

4. A baffle wall for water tube boilers consisting of a flexible apron fixedly secured by its upper edge, and means for raising and lowering its lower edge portion.

5. A baffle wall for water tube boilers consisting of a flexible apron fixedly secured by its upper edge, and raising and lowering mechanism connected to its lower edge adapted to vary the depth of the apron by folding it upwardly or downwardly.

6. In a water tube boiler, an adjustable baffle wall consisting of a continuous series of flexibly connected cross slats secured at the top and connected at the bottom to lifting mechanism for lengthening or shortening the lower portion of the wall.

7. In a water tube boiler, an adjustable baffle wall consisting of a continuous series

of flexibly connected cross slats secured at the top across a bank of tubes, a sheave wheel and means for rotating it, and a flexible connection between the sheave wheel and the lower edge of the baffle wall.

8. In a water tube boiler, in combination with a bank of tubes having an upper fixed baffle wall, an adjustable extension forming 55 a positively connected continuation thereof depending below the fixed wall, and means for raising or lowering it.

9. In a water tube boiler, in combination with a bank of tubes having an upper fixed 60 baffle wall, a flexible extension thereof depending below the fixed wall, and means for raising or lowering its lower edge.

10. In a water tube boiler, in combination with a bank of tubes having an upper fixed 65 baffle wall, a flexible extension thereof depending below the fixed wall, adapted to be turned upwardly at its lower edge portion, an upper transverse shaft having sheave wheels thereon, flexible connections between 70 the sheave wheels and the lower edge of the flexible extension, and means for actuating the shaft.

11. A baffle wall for water tube boilers consisting of a series of metal plates having 75 pivotally connected hinge lugs at one side thereof providing for abutting engagement and limited flexure of the plates, and means for reversing the lower portion of the wall and lifting it upwardly to shorten the effective 80 length of the wall.

12. A baffle wall for water tube boilers consisting of a series of metal plates having pivotally connected hinge lugs at one side thereof providing for abutting engagement 85 and limited flexure of the plates at their hinged joints, and means for reversing the lower portion of the wall and lifting it upwardly to shorten the effective length of the wall and for alternately lowering it to 90 lengthen the wall.

In testimony whereof I hereunto affix my signature.

DANA H. MAYO.
